US00D364988S

United States Patent [19]**Dardashti****Patent Number: Des. 364,988****Date of Patent: *** Dec. 12, 1995****[54] DISPLAY AND STORAGE ASSEMBLY**

[76] Inventor: **Shahriar Dardashti**, Atlantic, Inc.,
10240 Matern Pl., Santa Fe Springs,
Calif. 90670-0399

[*] Notice: The portion of the term of this patent
subsequent to Jun. 27, 2009, has been
disclaimed.

[**] Term: **14 Years**

[21] Appl. No.: **20,785**

[22] Filed: **Apr. 1, 1994**

CLAIM

The ornamental design for a display and storage assembly,
as shown and described.

DESCRIPTION

FIG. 1 is a front elevational view of a display and storage
assembly showing my new design;

FIG. 2 is a right side elevational view thereof; the left side
elevational view being a mirror image thereof;

(Description continued on next page.)

1 Claim, 22 Drawing Sheets

FIG. 3 is a rear elevational view thereof;
 FIG. 4 is a top plan view thereof;
 FIG. 5 is a bottom plan view thereof;
 FIG. 6 is a front elevational view of a second embodiment thereof;
 FIG. 7 is a left side elevational view thereof;
 FIG. 8 is a right side elevational view thereof;
 FIG. 9 is a rear elevational view thereof;
 FIG. 10 is a top plan view thereof;
 FIG. 11 is a bottom plan view thereof;
 FIG. 12 is a front elevational view of a third embodiment thereof;
 FIG. 13 is a right side elevational view thereof; the left side elevational view being a mirror image thereof;
 FIG. 14 is a rear elevational view thereof;
 FIG. 15 is a top plan view thereof;
 FIG. 16 is a bottom plan view thereof;
 FIG. 17 is a front elevational view of a fourth embodiment thereof;
 FIG. 18 is a left side elevational view thereof;
 FIG. 19 is a right side elevational view thereof;
 FIG. 20 is a rear elevational view thereof;
 FIG. 21 is a top plan view thereof;
 FIG. 22 is a bottom plan view thereof;
 FIG. 23 is a front elevational view of the fifth embodiment thereof;
 FIG. 24 is a right side elevational view thereof; the left side elevational view being a mirror image thereof;
 FIG. 25 is a rear elevational view thereof;
 FIG. 26 is a top plan view thereof;
 FIG. 27 is a bottom plan view thereof;
 FIG. 28 is a front elevational view of a sixth embodiment thereof;
 FIG. 29 is a left side elevational view thereof;
 FIG. 30 is a right side elevational view thereof;
 FIG. 31 is a rear elevational view thereof;
 FIG. 32 is a top plan view thereof;
 FIG. 33 is a bottom view thereof;
 FIG. 34 is a front elevational view of a seventh embodiment thereof;
 FIG. 35 is a left side elevational view thereof;
 FIG. 36 is a right side elevational view thereof;
 FIG. 37 is a rear elevational view thereof;
 FIG. 38 is a top plan view thereof;
 FIG. 39 is a bottom plan view thereof;
 FIG. 40 is a front elevational view of an eighth embodiment thereof;
 FIG. 41 is a left side elevational view thereof;
 FIG. 42 is a right side elevational view thereof;
 FIG. 43 is a rear elevational view thereof;
 FIG. 44 is a top plan view thereof;
 FIG. 45 is a bottom plan view thereof;
 FIG. 46 is a front elevational view of a ninth embodiment thereof;
 FIG. 47 is a left side elevational view thereof;
 FIG. 48 is a right side elevational view thereof;
 FIG. 49 is a rear elevational view thereof;
 FIG. 50 is a top plan view thereof;
 FIG. 51 is a bottom plan view thereof;
 FIG. 52 is a front elevational view of a tenth embodiment thereof;
 FIG. 53 is a left side elevational view thereof;
 FIG. 54 is a right side elevational view thereof;
 FIG. 55 is a rear elevational view thereof;
 FIG. 56 is a top plan view thereof;

FIG. 57 is a bottom plan view thereof;
 FIG. 58 is a front elevational view of an eleventh embodiment thereof;
 FIG. 59 is a left side elevational view thereof;
 FIG. 60 is a right side elevational view thereof;
 FIG. 61 is a rear elevational view thereof;
 FIG. 62 is a top plan view thereof; and,
 FIG. 63 is a bottom plan view thereof.

The broken line showing in FIGS. 2, 7, 8, 13, 18, 19, 24, 29, 30, 35, 36, 41, 42, 47, 48, 53, 54, 59, and 60 are for environmental purposes only and form no part of the claimed designs.
